(57) CLAIM

I claim the ornamental design for an outdoor barbecue grill lid, as shown and described.

DESCRIPTION

FIG. 1 is a top perspective view of the outdoor barbecue grill lid in a closed position;

FIG. 2 is a front view of the outdoor barbecue grill lid in the closed position;

FIG. 3 is a back view of the outdoor barbecue grill lid in the closed position;

FIG. 4 is a right side view of the outdoor barbecue grill lid in the closed position;

FIG. 5 is a left side view of the outdoor barbecue grill lid in the closed position;

FIG. 6 is a top view of the outdoor barbecue grill lid in the closed position;

FIG. 7 is a bottom view of the outdoor barbecue grill lid in the closed position;

FIG. 8 is a top perspective view of the outdoor barbecue grill lid in a partially open position;

FIG. 9 is a front view of the outdoor barbecue grill lid in the partially open position;

FIG. 10 is a back view of the outdoor barbecue grill lid in the partially open position;

FIG. 11 is a right side view of the outdoor barbecue grill lid in the partially open position;

FIG. 12 is a left side view of the outdoor barbecue grill lid in the partially open position;

FIG. 13 is a top view of the outdoor barbecue grill lid in the partially open position;

FIG. 14 is a bottom view of the outdoor barbecue grill lid in the partially open position;

FIG. 15 is a top perspective view of the outdoor barbecue grill lid in a fully open position;

FIG. 16 is a front view of the outdoor barbecue grill lid in the fully open position;

FIG. 17 is a back view of the outdoor barbecue grill lid in the fully open position;

FIG. 18 is a right side view of the outdoor barbecue grill lid in the fully open position;

FIG. 19 is a left side view of the outdoor barbecue grill lid in the fully open position;

FIG. 20 is a top view of the outdoor barbecue grill lid in the fully open position; and,

FIG. 21 is a bottom view of the outdoor barbecue grill lid in the fully open position.
